SPECTACLE DISPLAY RACK

Anthony De Witt Glover, Austin, Tex.

Application March 13, 1958, Serial No. 50,022

Term of patent 14 years

(Cl. D80—9)

Fig. 1.

Fig. 2.

Fig. 1 is a perspective view of a spectacle display rack embodying my new design, the spectacles shown in broken lines being for illustrative purposes only; and

Fig. 2 is also a perspective view thereof but taken from the opposite side and omitting the spectacles.

The dominant features of the design are shown in full lines.

I claim:

The ornamental design for a spectacle display rack, substantially as shown and described.
